Fig. 5

Figure 1 is a front elevation of a pull, showing my new design.

Fig. 2 is a top view of the pull.

Fig. 3 is a side view.

Fig. 4 is a perspective view.

Fig. 5 is an enlarged sectional view taken along the line 5—5 in Fig. 4.

The design is particularly characterized by the contrasting colors of the pull proper and the escutcheon plate which is disposed adjacent the mounting plate.

I claim:

The ornamental design for a pull, substantially as shown and described.
